UNITED STATES PATENT OFFICE.

RAY S. WILBUR, OF LYNDHURST, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,383,584.

Specification of Letters Patent. Patented July 5, 1921.

Application filed December 27, 1918. Serial No. 268,506.

To all whom it may concern:

Be it known that I, RAY S. WILBUR, a citizen of the United States, residing at Lyndhurst, in the county of Bergen, State of New Jersey, have invented certain new and useful Improvements in Telephone Systems, of which the following is a full, clear, concise, and exact description.

The invention relates to a telephone system and it has more particularly to do with an arrangement for transmitting signaling currents outside of the range of ordinary telephone or voice currents over a transmission line for the purpose of giving a visual or audible indication to an attendant or a subscriber.

In long transmission lines it is common to provide amplifying or repeating devices for reinforcing or repeating voice currents, and also to provide certain combinations of inductance and capacity for preventing attenuation of the voice currents. All of this apparatus is ordinarily designed for the efficient transmission of currents of voice or telephone frequency. It is desirable and necessary to transmit over the same transmission line, currents of much lower frequency than that of the voice currents, for the purpose of signaling between attendants or between subscribers; for example, signaling current usually of a frequency adapted to actuate a bell, which signaling current is commonly known in the art as ringing current. These ringing currents are attenuated to a greater degree than the voice currents, since the transmission line is not designed to transmit currents of the ringing frequency at the highest efficiency. It has therefore been common to provide, usually at a repeater station, an electromagnetic device which would respond to ringing current coming in over one end of the line, which, in responding, would connect another source of ringing current to the line on the other side of the repeater, thus, in effect, repeating or relaying the ringing current. As a certain definite strength of ringing current is necessary to operate a ringing current responsive device, the range over which such device could be operated is determined by the impedance of the line between the point where the ringing current is impressed on the line and the location of the ringing responsive device, and also by the impedance of certain apparatus ordinarily associated

with the repeater or amplifier usually employed for voice currents. Thus, the usual arrangement has been to bridge a ringing response relay across the transmission line, either in the neighborhood of the repeating apparatus or across the midpoint of the output coil of such repeating apparatus. When such connection is made, it is obvious that the bridged input coil of the repeater forms a parallel circuit or shunt around the ringing response relay. Under these conditions the ringing range could not be increased beyond a certain point which is determined not merely by the impedance of the line up to the point of connection of the ringing response relay but also the impedance of the shunt circuit.

It is an object of the present invention to increase the ringing range of a transmission line which includes repeating apparatus, and in accordance with a feature of the invention this object is attained by inserting in the transmission line, beyond the point of connection of the ringing response device or relay, an impedance which is high to currents of ringing frequency and which is low to currents of talking frequency, which impedance so decreases the shunt effect of the input coil of the repeater or amplifying device as to render such shunting effect almost negligible for currents of ringing frequency.

The invention will be best understood from the specification and annexed drawing, in which the figure is a diagrammatic representation of a portion of the transmission line including the apparatus at a repeater station included in such line.

In the drawing, L^1 and L^2 and L^3 and L^4 represent opposite ends of a telephone transmission line extending between two widely separated points. Associated with such transmission line is a pair of amplifying devices 1 and 2. The amplifying device 1 is arranged to amplify currents impressed upon the conductors L^1 and L^2 and to impress such amplified currents on the conductors L^3 and L^4 . Similarly the amplifying device 2 is arranged to amplify currents impressed on the conductors L^3 and L^4 , and to impress such amplified currents on the conductors L^1 and L^2 . These amplifiers are of the well-known discharge tube type, including the heated filaments 3 and 4, the plate electrodes 5 and 6 and the auxiliary

or modifying electrodes 7 and 8. The filaments 3 and 4 are heated by means of the heating battery 9-9'. The input circuit of the amplifier 1 includes a source of potential 10, the filament 3, auxiliary electrode 7 and winding 11 of the input coil. The other winding 12 of the input coil is bridged across the line conductors L^1 and L^2 . The terminals of the input coil 12 are connected through adjustable contacts to the potentiometer 13, which is used for adjusting the gain of the repeater. Similarly the input circuit of the amplifier 2 includes a source of potential 10', filament 4, the auxiliary electrode 8 and a winding 14 of the output coil. The winding 15 of the output coil is connected through movable contacts with the potentiometer 16. The output circuit of the amplifier 1 may be traced from a source of potential 17, through retardation coil 18, and thence over parallel branches one extending through the plate electrode 5, filament 3, back to battery 17, and the other through the output coil 19 back to the other side of the battery. Similarly the output circuit of the amplifier 2 includes the source of potential 17' and retardation coil 18', and two parallel branches, one including the plate electrode 6, and filament 4; and the other including the output coil 20.

Voice currents impressed upon the line L^1-L^2 normally pass through the armature and normal contacts of the relay 21 through condensers 22, windings 23 and 24 of the output coil of the amplifier 2, and from mid-point of the windings 23 and 24 through a filter comprising inductances 26 and bridge condensers 27 through the potentiometer 13 and the input coil 12 of the amplifier 1. It will be noted that the conductor L^2 includes a normally closed contact of the relay 28. The amplified currents pass through the winding 19 of the output coil and are therefore induced in the windings 29 of the output coil of the amplifier 1, from whence they pass through condensers 30 and armatures and normal contacts of the relay 31 to the line L^3-L^4 .

Voice currents impressed upon the line L^3-L^4 pass through the armature and normal contacts of the relay 31 through condensers 30 and through the windings 29 of the output coil of the amplifier 1, and from the mid-point of such windings through the filter, comprising inductances 32 and bridge capacity 33, through the potentiometer 16 to the input coil 15 of the amplifier 2. The conductor L^4 includes a normal contact of the relay 28. The currents amplified by the amplifier 2 pass through the output coil 20 and are induced in the output coils 23 and 24 and pass from thence through the condensers 22, normal contact and armature of the relay 21 to the line L^1-L^2 . The filters referred to are for the purpose of filtering out currents outside the range generally encountered in voice currents and for preventing the passage of currents of such frequencies through the amplifiers. Potentiometers 13 and 16 are adjusted to give the maximum gain for currents of voice frequency. Connected across the windings 23 and 24 of the output coil of amplifier 2 is the artificial line 25, the purpose of which is to balance the line section L^1-L^2 . Similarly the artificial line 26 is connected across the output coil 29 for the purpose of balancing line section L^3-L^4 . The entire circuit arrangement shown and thus far described is designed primarily for the efficient transmission and amplification of currents of voice frequency.

For signaling purposes, however, current having a frequency much below that of the voice frequency, preferably approximating 16 $\frac{2}{3}$ cycles, is ordinarily used. There is provided at the repeater station bridged across the conductors L^1 and L^2 a relay 35 which is tuned to respond to current of ringing frequency, that is about 16 $\frac{2}{3}$ cycles, and to present a high impedance to currents of voice frequency. A similarly tuned relay 36 is connected across the conductors L^3 and L^4 .

Ringing current impressed upon the line L^1-L^2 at the distant end of the transmission line encounters at the repeater station two parallel circuits, one of which is directly across the conductors L^1 and L^2 and includes the relay 35; the other includes the condensers 22, windings 23 of the output coil of the amplifier 2, condensers 37, the artificial line 25 or a parallel branch of said last mentioned parallel circuit, which may be traced from the mid-points of the windings 23-24, through the filtering arrangement and input coil of the amplifier 1 including the left-hand normal contacts of the relay 28. It will be observed that the relay 35 is connected directly across the line and that there is included in the shunt circuits just traced the condensers 22, in addition to various other inductances and capacity.

It is possible to select for the condensers 22 condensers which are designed to present little or no impedance to currents of voice frequency, but which, together with the inductance in the shunt circuits just traced, present a very high impedance to currents of ringing frequency. Therefore, practically all of the ringing current is diverted through ringing response relay 35. As there is a certain definite minimum of current upon which ringing response relays, such as 35, may be made to operate satisfactorily, it is obvious that by diverting practically all the ringing current transmitted over the line through it, that the range or length of transmission line over which such ringing response relay can be operated is greater than would be the case if no pre-

cautions were taken to prevent the shunting of such relay by other apparatus bridged across the transmission line.

The relay 35 in operating opens a circuit 5 of the normally energized relay 38, which in releasing its armature closes a circuit from battery 39 through the right-hand winding of the relay 28, contact and armature of the relay 38 to ground, and from battery through 10 the relay 31, contact and armature of the relay 38 to ground. The relay 28 in operating establishes short circuits about the input coil 12 of amplifier 1 and the input coil 15 of amplifier 2, and thus prevents the passage 15 of the ringing current through such amplifiers. The operation of the relay 31 connects a source of ringing current indicated by the plus and minus signs to the conductors L^3 and L^4 . This source of ringing current may be of the same frequency as that impressed upon the line L^1-L^2 , or it may be 20 of some other frequency.

It will be obvious that ringing currents impressed upon line L^3-L^4 will cause the 25 operation of the relay 36 identically as in the case of relay 35, and the consequent de-energization of the normally energized relay 40 will cause the operation of the relays 28 and 21. Relay 21 will connect a source 30 of ringing current to the line conductors L^1 and L^2 .

What is claimed is:

1. In combination with a telephone transmission line, a repeater, a conductive bridge 35 connected across said line for associating said repeater therewith, an electromagnetic responsive device responsive to currents having a frequency outside of the voice range bridged across said transmission line, and 40 impedance means included in said repeater bridge presenting high impedance to currents outside the voice range.

2. In combination with a telephone transmission line, a repeater, an input circuit for 45 said repeater bridged across said line, an electromagnetic ringing current responsive device also bridged across said line and tuned to respond to currents of ringing frequency, and impedance means included in said repeater bridge presenting high impedance to 50 currents of ringing frequency.

3. In combination with a telephone transmission line, a telephone repeater, an input

circuit for said repeater bridged across said telephone line, a ringing current relay 55 bridged across said transmission line tuned to respond to currents of ringing frequency, and impedance means included between the point of connection of the ringing relay bridge and the input circuit of the repeater 60 to render the repeater bridge of high impedance to currents of ringing frequency.

4. In combination with a telephone transmission line, of a plurality of repeaters associated therewith, an input coil of one of 65 said repeaters bridged across said transmission line, an output coil of the other of said repeaters included in series with said transmission line, a ringing responsive relay bridged across said transmission line, and 70 impedance means for preventing the shunting of ringing current from said relay bridge through the bridge formed by the said output and input coils.

5. In combination with a telephone transmission line, a plurality of repeaters included in said line one of said repeaters having an input coil connected in bridge across said line and another having an output coil connected in series with said line, a ringing 80 responsive relay connected in bridge across said line intermediate one end thereof and said output coil, and means controlled by said ringing responsive relay to connect a source of ringing current to said line between 85 said input coil and the other end of said line.

6. In combination with a telephone transmission line, a pair of repeaters associated therewith, an input coil for each of said 90 repeaters connected across said transmission line, an output coil for each of said repeaters connected in series with said transmission line, a pair of ringing responsive relays, each of said relays connected across said transmission line between an end thereof and said output coil of the adjacent one of said repeaters, and means controlled by each of said ringing responsive relays for connecting a source of ringing current to said line between 95 the opposite end thereof and the adjacent one of said repeaters.

In witness whereof, I hereunto subscribe my name this 20th day of December, A. D. 1918.

RAY S. WILBUR.
